UNITED STATES PATENT OFFICE.

WILLIAM MARSHALL HUSKISSON, OF LONDON, ENGLAND.

SUBMARINE MINE.

SPECIFICATION forming part of Letters Patent No. 542,732, dated July 16, 1895.

Application filed November 22, 1894. Serial No. 629,863. (No model.) Patented in England September 16, 1893, No. 17,447.

To all whom it may concern:

Be it known that I, WILLIAM MARSHALL HUSKISSON, civil engineer, a British subject, residing at 127 Ladbroke Grove, London, in 5 the county of Middlesex, England, have invented certain new and useful Improvements in and Relating to Submarine Mines, (for which I have obtained a patent in Great Britain, No. 17,447, bearing date September 16, 10 1893), of which the following is a specification.

My invention relates to a submarine mine which shall explode automatically when a ship comes within a predetermined distance 15 of it—that is to say, it does not require to be struck by the ship or to be fixed by an operator aboard another ship or ashore in order to explode it. In order to accomplish this I employ a Hughes induction-balance, together 20 with a case of explosive moored at sea, the secondary coils of the balance controlling a device which switches the main current from the primary onto the secondary coils when the balance is destroyed by a passing ship. A 25 fuse is arranged in series with one of the secondary leads which will "blow" with this current and explode the mine. The nature of this invention and in what manner the same 30 is to be performed is particularly described and ascertained in and by the following statement, reference being had to the accompanying drawings, in which—

Figure 1 is a diagram illustrating the disposition of the electrical circuits and the connections of the apparatus. Figs. 2 and 2^a together form a plan, part in section, of my automatic switching device. Fig. 3 is a front elevation, part in section, of my automatic switching device. Fig. 4 is a side sectional elevation of the switchboard H'. Fig. 5 is a 35 sectional elevation of the mine at sea. Fig. 6 is a plan, part in section, across coils C and C' of the mine at sea. Fig. 7 is a detail view illustrating method employed for making 40 water-tight the joints of the cases D' and d' which contain the coils of the Hughes induction-balance. Fig. 8 is a detail view showing in section the detonator and fuse for exploding the mine. Fig. 9 is an elevation showing 45 the tub and case holding the balancing-coils. Fig. 10 is a plan of the same.

Similar letters and figures of reference indicate like parts.

Having described above the general principles underlying my said apparatus, I now 55 more specifically refer to its construction.

A is the outside casing of the mine, preferably composed of non-magnetic material, (see Figs. 5 and 6,) fitted with grappling-hooks A', a movable cover A², and a mooring-ring A³, 60 and inclosing a lower compartment B for holding the explosive, divided by the diaphragm B' with its movable cover B² from the upper compartment containing a case D', secured to the walls of the mine by the wooden chocks 65 D². This case D', which may be of porcelain, stoneware, or other non-magnetic material, contains two insulated wire coils, C the primary and C' the secondary coils, of one part of a Hughes' induction-balance. The coils are 70 wound on a former D composed of insulating material and afterward fitted into the case D'. The leads are passed through stuffing-boxes and glands which form part of D'—i. e., primary lead 15 through E² and 14 through E⁴, 75 secondary lead 13 through E³ and 20 through E⁵. A cover E composed of the same material as D', flanged up at its edge, is bolted onto D' by the bolts E', (see Fig. 7,) the cavity D³ being afterward grouted in with bitumen or 80 cement or other suitable composition for making a good joint. The coils C and C' do not entirely fill up the interior of the case D', and resin-oil is poured in through the plug-hole E⁶ and entirely fills up the vacant space. A plug 85 is afterward screwed in and sealed, all this being done to reduce the chances of electrical leakage occurring.

The primary and secondary leads 15 14 13 90 20 are led down the walls of the mine to which they are cleated at intervals (13 being broken on passing through G) and are made up into one cable 19, which is passed through the stuffing box and gland F to the outside of the mine, where it is armored with lead 95 or some high resistance and non-magnetic material for several feet in proximity to the mine. It is lashed to the mooring-rope, and from thence it is led away to the shore. The secondary lead 13 is passed through the 100 socket G (made of insulating material) and broken, the ends being soldered to two

aluminium rings G' and G^2 , which are insulated from one another, and embedded in the socket G . A round fuse K , having two rings K' and K^2 insulated from one another on its barrel, fits in the hole in the center of G , K' fitting tightly in G' and K^2 in G^2 . These rings have two pins projecting inside the fuse riveted to them. The latter are electrically connected by the fine fuse-wire K^3 , around 15 which is a mixture of fine mealed powder and gun-cotton, the rest of the fuse containing mercurial fulminate. The fuse K is forced home by the grommet L' , screwed against it by the plug L , a second plug L^3 , 20 squeezing a grommet L^2 against L , L^3 being prevented from slackening back by the screwed set L^4 . One end of the tube N is screwed into G , and the cavity G^3 is filled up with bitumen or other insulating material. N is then filled 25 up with a detonating charge and the top is closed by the plug-cap N' and the washer N^2 . After the socket G has been fitted into the mine and the cable 19 has been tightened up in the stuffing-box F , then the bottom of the 30 mine is filled up with bitumen or other insulating material at F' , so that electrical and mechanical joints are in one solid block of bitumen. The case d' , covered by e , Figs. 9 and 10, inclose similar coils, similarly disposed with regard to one another, as those inclosed by D and E , and is the other part of the balancing-coils of the Hughes induction-balance placed ashore or aboard ship, primary leads 18 and 17 passing through stuffing-boxes and glands e^2 and e^4 , secondary leads 16 and 12, through e^3 and e^5 , respectively, the case d' being supported on the chocks M' , in 35 the tub of resin-oil M .

The automatic switching device (illustrated 40 by Figs. 2, 3, and 4) placed ashore or aboard ship is a dynamometer, with the fine-wire floating-coil p , in two parts, the winding, Fig. 1, being similar to that of Ampère's astatic rectangles, in order to neutralize terrestrial effects. They are wound on a former, of the 45 shape shown, in some hot insulating substance which sets solid when cold. The former is afterward removed, leaving the solid coils. These are placed within the stationary ring-coil P , so as to be unaffected by external influences. They are rigidly connected to the aluminium blade R , to which one of its terminal wires is soldered, the other terminal wire l dipping into the mercury-cup 50

55 n . A wire i , soldered to R , dips into the mercury-cup m . These mercury-cups are in electrical connection with the binding-screws O^4 and O^2 , which are coupled up to the secondary leads 16 and 20 of the Hughes induction-balance m , being also in electrical connection with O^3 , which is coupled up to the terminal 10 of the exciter or local battery 8, Fig. 1. The blade R is suspended at R' by the thread T , secured to the eyebolt s^2 and adjusted by the thumb-nut S' , carried by the porcelain column S , which is secured to O^2 by the screws s , Fig. 2. One end of R floats between the *vis-à-vis* poles

of the electromagnet a , it being balanced by the adjustable balance-weight R^2 , which screws onto the opposite end. The fixed coils P wound on a former Q , to which is fitted a small tube g , allow coil p to have a slight movement without touching this winding. The shape of the outside coil P is, as nearly as practical considerations will allow, a closed 75 ring. Of the section shown for convenience of winding, the coil p would be one hollow ring if it could be made, this apparatus being so constructed in order to give the greatest turning movement with the least inertia, 80 the terminal wires of this coil P being connected to the binding-screws O and O' , which are coupled up to lead 17 of the Hughes induction-balance and contact-clip V^2 , Fig. 1, respectively, the wires being twisted round 85 one another for some distance near the instrument, which is built up of the several insulating-pieces Q , Q' , and Q^2 and mounted on the slab H and leveled by the four screws J , which are free to turn in sockets embedded 90 in the foundation I .

The electromagnet a before referred to is mounted on the slab H' by means of the bracket c and the lug f , Figs. 2 and 4. One pole a' is fixed. The other a^2 swings off the 95 pivots b , the terminal wire of one end of the winding of a being soldered to the core a^2 , the other end to the binding-screw r , which is coupled to the terminal 9 of the exciter 8. A small snug is on a^2 , on which rests the end of a lever h , which has a fulcrum h' , the other end of it arresting the lever W^2 controlled by the flat coil-spring W wound on the spindle W' and mounted on the slab H' . When released it will fly round off the center W' , 105 striking the insulating-bridge of the switch V , which it will carry with it. V is a double pole-blade switch working off the pivots V' , which are in electrical communication with the contact-clips y^2 , closing the circuits 110 through the clips V^2 V^2 and Z' and Z^2 in one position or breaking these and closing those through V^3 in the other position, Fig. 1.

Y is a double-pole switch swinging off the pivots Y' and engaging the clips Y^2 , and is 115 used for switching off the dynamo from the apparatus.

X is a double-pole safety-switch breaking the circuit from contact-clips V^3 V^2 to the leads 20 13 when not engaging contact-clips 120 X^2 X^2 .

A small indicator U is provided as a gage for position of R .

The circuits may be readily traced by the aid of the diagram, Fig. 1, where the plumed arrows indicate the course of the main current from the alternator 5, the naked arrows that of the induced currents, and the dotted arrows that of the auxiliary or exciter circuit.

In order to adjust the coils accurately, a 130 telephone is inserted between the leads 20 and 16 and a zero or noiseless position is obtained. Then the telephone is replaced by the instrument operating the switching device, which

is coupled up so that when the induced currents from the mine at sea, or rather the secondary coil at sea, overpower those from the secondary coil ashore then coil p will turn on 5 the thread T.

The action of the gear is as follows: Assume that the alternator 5 has been started. The operator then closes the switch Y, which puts the main current from the alternator 5 10 through the primary coils, and also through the coils P of the instrument, Fig. 1. He now looks to see that the blade R is directly under the pointer U. That being so, he knows that the insulation of the whole apparatus is 15 all right. So he at once closes the switch X, which places the secondary leads 20 and 13 in communication with the contact-clips V⁸ and V⁹. Say an induction-balance of the size, &c., to have a sensitive zone of ten feet, is in the 20 mine. Now a ship passes within six feet of it. At once the induced currents from the secondary coil C' at sea overpower those from the secondary coil ashore. The former cause 25 the coil p , Figs. 1, 2, and 3, to turn on T, so that the blade R strikes one of the vis-à-vis poles of the magnet a. This at once closes a 30 circuit which may be traced from exciter 8, lead 10, mercury-cup m, blade R, pole-piece a', coils a, lead 9, back to exciter 8. This current has excited the electromagnet a, whose 35 vis-à-vis pole a² swings to a', gripping the blade R between them. The snug on a', leaving the lever h, which at once releases the center W', which plies round, turning off the 40 switch V, strikes the insulating-bridge of the switch V, swings it out of gear with the contact-clips V², V³, Z', and Z², and into gear with the contact-clips V⁸ V⁹. The circuits 45 which have been closed by this action may be traced as follows: alternator 5, lead 6, pivot Y', switch Y, clip Y², pivot V', clip V³, lead 20, coil C', fuse K³, (this fuse will "blow" with this current and the arc will explode the 50 mine and blow up the ship,) lead 13, clip V⁸, switch V, pivot Y', clip Y², switch Y, pivot Y', lead 7, to alternator 5. The circuits which 55 have been broken may be traced as follows: alternator 5, lead 6, Y', Y, Y⁸, V², and V³, lead 14, coil C, leads 15 and 18, main coil, lead 17, 60 coil P, clip V² V' V', clip Y² Y' Y', lead 7, to alternator 5; also, Z', 12, 16, p, 20, C', 13, and Z², induced-current circuit, all this having 65 been done without any human aid and by the ship herself. The switch Y can be switched off to allow a friendly ship to pass into harbor in safety. For example, say a blockade-runner is waiting outside the mouth of a river for daylight, in order to take her bearings, and is sighted by an enemy's cruiser (before 70 she has been able to get into shelter) which forthwith gives chase. Now the operator on shore swings off the switch Y and lets the blockade-runner pass in safety. The cruiser seeing that the blockade-runner has gone over 75 the mined waters in safety comes on. The operator closes the switch Y and directly the cruiser comes within the sensitive zone of the

mine it automatically explodes. It is quite clear that such a mine is independent of tides.

I have only described one application of my invention, as, from this description, it will be evident that the balancing-coils ashore might be fitted into another mine or that the Hughes induction-balance might be of the type having one primary coil with a secondary coil in a conjugate position with regard to it. It is also clear that the electrical circuits could be arranged in various ways.

In the case of a pair of coils of a Hughes induction-balance moored or sunk in a nest of 80 torpedoes the switch V closes all the firing-circuits of these torpedoes when operated by W², Fig. 1, becoming released by the action of the electromagnet a, &c.

Again, in defending a harbor or river provided with forts the secondary lead can also be in series with the fuse in a gun sighted on the mine at sea, (the gun being elevated and depressed by independent mechanism to allow for rise and fall of tide,) so that when the 90 mine explodes so also will the gun be fired.

I am aware that there are various mines in use, such as mechanical mines, requiring to be struck by the ship, combined mines requiring skilled operators ashore using range-finders and closing circuits, &c., and also fitted with electrical circuit-closers which will 95 explode them when struck by a ship. All these present many disadvantages in practice, too numerous to enumerate here. With my 100 mine I eliminate all these difficulties and uncertainties, as when the ship ventures within a predetermined distance of the mine it automatically explodes; the ship, in fact, causing her own destruction.

Having now particularly described and ascertained the nature of my said invention and in what manner the same is to be performed, I declare that what I claim is—

1. In submarine mine apparatus, a vessel charged with explosive compound, a Hughes induction balance one part of which is contained within the vessel while another part thereof is situated at a distance, an electric fuse within the said vessel included in the 115 secondary circuit of the said induction balance, a current generator at a distance whose circuit is connected with the primary circuit of said induction balance and means in connection with the secondary circuit thereof whereby when a current passes through said 120 circuit, the circuit of the current generator is switched on to said secondary circuit and is thereby made to fire the electric fuse, substantially as described.

2. In submarine mine apparatus the combination of a mine or vessel charged with explosive compound, a Hughes induction balance, one primary and secondary coil of which is contained within said mine while the 130 secondary primary and secondary coil thereof are situated at a distance therefrom, an electrical fuse within the mine, adapted to explode the charge thereof and connected to the

secondary circuit of the said induction balance, a current generator at a distance from the mine, whose circuit is connected to the primary circuit of the Hughes induction balance, and an automatic switching device whereby an induced current, produced in the secondary circuit of the induction balance by a ship passing within the operative distance thereof causes the switch to connect the current generator circuit onto the said secondary circuit so as to explode the fuse of the mine by the generator currents, substantially as described.

3. The combination with a submarine mine of a Hughes induction balance, the primary

circuit of which is connected to the circuit of a current generator, while the secondary circuit (in which an electrical fuse contained in the mine is included) is connected to a switch apparatus, and means whereby when a current is induced in such secondary circuit, it will operate the switch so as to connect the circuit of the current generator, with the said secondary circuit, substantially as described.

Dated this 17th day of October, 1894.

WILLIAM MARSHALL HUSKISSON.
